UNITED STATES PATENT OFFICE.

LOUIS C. LOEWENSTEIN, OF LYNN, MASSACHUSETTS, ASSIGNOR TO GENERAL ELECTRIC COMPANY, A CORPORATION OF NEW YORK.

MEANS FOR CONTROLLING THE AIR-SUPPLY TO WATER-GAS GENERATORS.

1,134,754.

Specification of Letters Patent. Patented Apr. 6, 1915.

Application filed September 30, 1913. Serial No. 792,611.

To all whom it may concern:

Be it known that I, LOUIS C. LOEWENSTEIN, a citizen of the United States, residing at Lynn, county of Essex, State of Massachusetts, have invented certain new and useful Improvements in the Means for Controlling the Air-Supply to Water-Gas Generators, of which the following is a specification.

10 This invention relates to the manufacture of water gas and its object is to improve the quality and quantity of such gas by supplying a constant volume of air to the generator during the "blow" or heating up of the carbureter.

In the process of making water gas, the generator is filled with a deep bed of coal or coke, and a blast of air is admitted in the bottom of the generator under the grate, and 20 passes up through the fuel. The oxygen of the air unites with the heated carbon to form carbonic oxid. These products of partial combustion are then burned in the carbureter and superheater by admitting air 25 from the blower. The result of this combustion is intense heat in the carbureter which is taken up by the loose firebrick, or checker-brick, with which the carbureter and superheater are filled. The resulting carbonic 30 acid and nitrogen-products of complete combustion then pass off to the atmosphere through the stack valve. The degree and distribution of heat in the carbureter and superheater are entirely under control, and 35 can be adapted to the character of the oil used in the carbureter. When the temperature in the carbureter is of the proper amount, the air blasts are shut off, and all 40 combustion ceases. The stack valve is then closed and steam is admitted under the grate of the generator. The passage of this steam through the highly heated fuel produces non-luminous water gas. As this gas enters 45 the top of the carbureter it meets a spray of partially vaporized oil. The gas and the oil vapors pass together over the highly heated surfaces of the checker-brick, and the oil vapors are gasified and fixed in the presence of the non-luminous water gas. The result 50 is a thoroughly fixed and permanent illuminating gas, which passes on to be scrubbed, condensed and purified in the usual manner. This period of gas making is continued until the heat in the apparatus is reduced to a

point where it is not advantageous to continue. The oil and steam are then shut off, the stack valve opened, and the process of blowing and heating up is repeated. Alternations of this heating up or "blow," and of gas making, or "run," are continued, each 55 of which seldom exceeds six or eight minutes in duration, until it is necessary to stop and add fuel, or at longer intervals, clean the fire by removing the slag.

As can be seen in the above described 60 process, air is simply introduced to assist combustion; that is, a certain weight of oxygen is required for combining with the heated carbon in the generator in order to 65 form carbonic oxid, and a certain weight of oxygen is required in the carbureter for 70 burning the carbonic oxid and producing intense heat. The amount of oxygen required in the generator for producing carbonic 75 oxid, and the amount of oxygen required in the carbureter for complete combustion can be determined from the amount of carbon that is contained in the fuel fed to the generator. If the amount of carbon is definitely known, the amount of oxygen can also be 80 known, and therefore, the amount of weight of air which must be supplied to the generator in order to obtain efficient combustion of the carbon, and complete combustion of the carbonic oxid. It can, therefore, be seen that 85 the successful and efficient operation of a gas producing plant depends largely upon the constancy of volume or rather weight of air supplied and not upon the pressure under which this air is delivered. If the fire 90 is clean and free from clinkers, a half a pound of air pressure possibly would be sufficient to give the desired quantity of air per minute. If, however, the fire is in an 95 unhealthy condition owing to the formation of a blanket of clinkers over the grate, a higher pressure to blast the same quantity of air per minute through the fire is required. Therefore, any device which will control the air supplied in such a manner as to deliver 100 a constant weight of air regardless of the pressure necessary to force this air through the generator will be the most efficient device for gas making.

The necessity of supplying a constant volume or weight of air during the process of gas making, although recognized, has not been satisfactorily accomplished. Usually 105

an air meter in the shape of a Venturi tube is placed in the discharge end of the compressor, whose object is to measure the amount of air flow on the discharge end of the blower. It can, however, be readily seen that this air meter will not perform the function intended because the pressure on the discharge end of the compressor will continually vary in order to deliver a constant volume of air due to varying resistances in the generator. If the air meter registers the correct amount of air or oxygen supplied when the discharge pressure is $\frac{1}{2}$ of a pound it will no longer register the correct weight of air when the pressure is increased or decreased; that is, the air meter on the discharge end will only measure constant volume at various densities, hence not constant weight of air or oxygen. We know that 14,000 cubic feet of air under $\frac{1}{2}$ of a pound pressure contains less weight of oxygen than 14,000 cubic feet of air under one pound pressure. Hence, the indications of a constant volume at the discharge end of the compressor do not necessarily mean a constant weight of air or oxygen. Again this meter as installed does not automatically control the supply of a constant weight of air, but simply furnishes a means of indicating what is happening at the discharge end of the compressor and it is left to the operator to so change the speed of his blower that this volume can remain fairly constant. In all the installations that the applicant has been able to study it was not possible for the operator to be continually controlling the speed of the compressor so that a constant volume could be secured.

The correct place to measure constant volume is at the suction end of the compressor, where the air conditions remain practically constant. Changes in atmospheric and barometric conditions are the only things that would influence the density, temperature and saturation of the air at this point. By measuring either automatically or otherwise, the volume or weight of air delivered at the suction end of the compressor, a much more accurate means of control is obtained.

In carrying out my invention I prefer to use a centrifugal air compressor, driven by a suitable motor which is controlled by a constant volume governor in the air supply conduit of such compressor, controlling the speed of the impeller thereof. As the pressure delivered by a centrifugal compressor is directly proportional to the square of the speed of the impeller, the constant volume governor will vary the pressure sufficiently to overcome restrictions in the plant without varying the weight or volume of air.

In the accompanying drawing, Figure 1 is a diagrammatic view of a gas generator and carbureter supplied with air by a centrifugal compressor equipped with a con-

stant volume governor, and Fig. 2 is a side view of the governor on a slightly larger scale.

1 indicates the generator, connected by a pipe 2 with the carbureter 3 from which the products of combustion pass off by the stack 4. Steam can be supplied to the generator and the carbureter by the pipes 5, 6, respectively, and oil can be fed into the carbureter by the pipe 7. The fixed gas is conducted from the carbureter by the pipe 8.

The air blast is supplied under the grate of the generator by the pipe 9, and to the carbureter by the pipe 10, both pipes being connected to the outlet of a centrifugal air compressor 11. In the drawing this compressor is shown as driven by a steam turbine 12 taking steam from a main 13. A throttle valve 14 controls the flow of steam, and is governed by a speed-responsive device 15.

At some suitable point in the air supply conduit of the air compressor, preferably in the intake 16, is located the constant volume governor comprising a float 17 attached to a stem 18, and located in an inverted frustoconical pipe section 19 connected by an elbow 20 with the inlet flange of the compressor. The stem 18 projects up through the elbow 20, and is connected to a beam 21 pivoted at 22 and carrying a sliding counterweight 23. A dash-pot 24 steadies the movements of this beam, one end of which is operatively connected (as by means of a lever 25 and link 26) with the floating lever 27 which actuates the throttle valve 14.

The sliding weight 23 is set at the graduation mark on the beam 21 which indicates the amount of air in cubic feet per minute that the plant requires. The float 17 will then assume a definite (herein designated normal) position with relation to the conical pipe 19 when the unit is brought to speed. If at any instance the fuel in the generator becomes more densely packed, or if the generator is slowly getting into an unhealthy condition by the formation of a blanket of clinker, the resistance to air flow through the generator is increased. Against this increased resistance the compressor can no longer deliver the required volume of air, so that momentarily a less quantity is drawn through the inlet. But just as soon as this occurs, the float 17 can no longer remain in its normal position because it is not sustained by the original volume of air. It therefore descends and pulls down the beam 21, thereby opening the throttle valve 14, and speeding up the compressor. This gradually increases the air pressure until it is sufficiently high to overcome the additional resistance in the generator and thus again forces the required volume of air through the apparatus. The constant volume governor thus responds instantly to any change

of condition in the plant and keeps the volume of air supplied by the compressor constant. This enables the generator to operate most economically and insures the complete combustion of the fuel in the time allotted to the "blow." The operator therefore has to see merely that the charge of fuel is of the proper quantity and that the blast continues during the time calculated to be necessary to fully consume said charge, leaving it to the constant volume governor to insure the constant delivery of the proper weight of air. This tends to better efficiency in operation and a more uniform product.

15 In accordance with the provisions of the patent statutes, I have described the principle of operation of my invention together with the apparatus which I now consider to represent the best embodiment thereof; but

20 I desire to have it understood that the apparatus shown is only illustrative, and that the invention can be carried out by other means.

What I claim as new and desire to secure by Letters Patent of the United States, is:—

1. The combination with a water gas plant,

of a compressor for supplying air thereto, a regulator for the compressor, and means responsive to the volume of air entering the suction side of the compressor for controlling the regulator. 30

2. The combination with a water gas plant of a centrifugal compressor for supplying air thereto, a motor for driving the compressor, and means controlled by the volume 35 of air entering the suction side of the compressor for regulating the motor whereby a constant weight of air is delivered by the compressor.

3. The combination with a water gas plant, 40 of a centrifugal compressor for supplying air thereto, a motor for driving said compressor, and a constant volume governor in the air supply conduit of said compressor for controlling the speed of said motor. 45

In witness whereof, I have hereunto set my hand this 25th day of September 1913.

LOUIS C. LOEWENSTEIN.
